US00D473206S

(12) **United States Design Patent** (10) Patent No.: **US D473,206 S**
Sasago et al. (45) Date of Patent: **** Apr. 15, 2003**

(54) **COMBINED DISC PLAYER WITH RADIO
RECEIVER AND TAPE RECORDER**

D455,415 S * 4/2002 Suzuki D14/168

(75) Inventors: **Osamu Sasago**, Tokyo (JP); **Hidefumi Goto**, Tokyo (JP)

OTHER PUBLICATIONS

(73) Assignee: **Sony Corporation**, Tokyo (JP)

Catalog, "Sony System Stereo, CMT-J100", p. 14, Sony Corporation (Sep. 2001).

(**) Term: **14 Years**

* cited by examiner

(21) Appl. No.: **29/158,988**

Primary Examiner—Nanda Bondade

(22) Filed: **Apr. 15, 2002**

(74) Attorney, Agent, or Firm—Rader, Fishman & Grauer PLLC

(51) LOC (7) Cl. **14-01**

(57) **CLAIM**

(52) U.S. Cl. **D14/168**

The ornamental design for a combined disc player with radio receiver and tape recorder, as shown.

(58) Field of Search **D14/135-136, D14/156-157, 160-165, 167-168, 188, 193-198; 369/75.1, 75.2, 77.1, 77.2; 455/344, 347-351**

DESCRIPTION

(56) **References Cited**

FIG. 1 is a perspective view of a combined disc player with radio receiver and tape recorder showing my new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; and, FIG. 7 is a bottom plan view thereof.
